JOSEF RENZ, OF NEW YORK, N. Y.

PNEUMATIC-VALVE MECHANISM.

No. 883,065.

Specification of Letters Patent. Patented March 24, 1908.

Application filed January 31, 1907. Serial No. 355,020.

To all whom it may concern:

Be it known that we, THEODORE VRANA and BRETISLAV SCHIBA, subjects of the Emperor of Austria-Hungary, and residents of the city of New York, borough of Manhattan, in the county and State of New York, have invented a new and Improved Pneumatic-Valve Mechanism, of which the following is a full, clear, and exact description.

10 The invention relates to automatic piano players and similar instruments, and its object is to provide a new and improved pneumatic valve mechanism, which is simple and durable in construction and arranged to insure a quick response of the pneumatic and consequently of the piano action, to render the valve mechanism noiseless and to allow convenient access to the interior parts for making repairs whenever necessary.

15 The invention consists of novel features and parts and combinations of the same, which will be more fully described hereinafter and then pointed out in the claims.

20 A practical embodiment of the invention is represented in the accompanying drawings forming a part of this specification, in which similar characters of reference indicate corresponding parts in both the views.

25 Figure 1 is a cross section of the improvement; and Fig. 2 is a transverse section of the same on the line 2—2 of Fig. 1.

30 The valve chest A of the pneumatic valve mechanism is provided with a suction chamber B connected with a main suction chamber C, for continually drawing air out of the suction chamber B. Directly below the suction chamber B is arranged a diaphragm chamber D having its top closed by a diaphragm E forming part of the bottom of the 35 suction chamber B. From the diaphragm chamber D leads a port F to a channel F' connected by a nipple G' with a tube G connected with an opening in the tracker board, so that when the note sheet brings one of its apertures in register with the tracker board 40 opening, then air passes through the tube G into the diaphragm chamber D, to cause the diaphragm E to move upward owing to the suction within the suction chamber B. The 45 channel F' also leads to a minute port F², opening into the suction chamber B, to drive air out of the channel F' and tube G, to allow a quick return of the diaphragm E. Directly above the suction chamber B is arranged a valve chamber H, from which leads 50

a channel H' into a pneumatic I by way of the fixed member I' thereof, and which fixed member is secured to the under side of the valve chest A. The movable member I² of the pneumatic I is connected with a rod J 60 guided in a guide-way A' formed on the valve chest A, and on the said rod J is secured or formed a button J' engaging the rocker K of a piano action, so that when the pneumatic I collapses, the rod J imparts a swinging motion to the rocker K, so as to cause the hammer of the piano action to strike and sound the corresponding string.

65 Within the valve chamber H is arranged a double valve L having spherical valve faces L', L² of leather or like soft material, and adapted to be seated on the valve seats N and O secured on the bottom and top of the valve chamber H, respectively, the valve seat N serving to establish communication 70 between the suction chamber B and the valve chamber H and consequently with the pneumatic I, to collapse the latter whenever the valve L moves off the seat N. The other valve seat O normally connects the valve chamber H with the atmosphere. The valve stem L³ of the valve L rests at its lower end on a disk or button E' secured to the diaphragm E at the middle thereof, so that when the diaphragm E is caused to move upward, as previously explained, then the valve L is lifted and consequently the valve face L' moves off the seat N while the valve face L² moves onto the seat O, thus connecting the chambers B and H with each other 75 and closing the valve chamber H to the atmosphere. The valve stem L³ of the valve L is mounted to slide in suitable bearings P and P' secured to the valve seats N and O, respectively, and which latter are preferably 80 made of metal.

85 In order to obtain convenient access to the interior parts of the valve mechanism, the valve chest A is preferably made in two sections A² and A³, hinged together by a hinge 90 A⁴ made of canvas, leather or like material, the free ends of the sections A², A³ being normally fastened together by a cover plate A⁵ secured to the sections A², A³ by suitable screws A⁶ or like fastening devices.

95 As shown in the drawings, the chambers B, D and the channel F' are formed in the lower section A³ while the chamber H is formed in the upper section A², and the channel H' extends through both sections, as in- 100 105 110

dicated in Fig. 1. Now on removing the rod J and the cover plate A⁵ the top section A² can be readily swung into an open position, to permit the operator to readily gain access to the valve and diaphragm. It will also be seen that on removing either seat N or O the valve L can be removed for repairs or other purposes.

It is understood that the valve seats O, N, 10 the valve L and the diaphragm E are in axial vertical alinement, and when air passes from the tracker board by way of the tube G and pipe F to the diaphragm chamber D, then the diaphragm E is caused to move upward 15 owing to the suction in the suction chamber B. Now when the diaphragm E moves upward it lifts the valve L, so that the valve chamber H is closed to the atmosphere by the valve surface L' seating on the seat O, 20 and communication is established between the suction chamber B and the valve chamber H owing to the valve surface L' moving off the seat N (see Fig. 2). When this takes place the air is drawn out of the pneumatic I by way of the channel H', chamber H and seat N opening into the suction chamber B, and consequently the pneumatic I collapses 25 and the piano action is actuated, as above explained.

30 As soon as the tracker board opening is closed by the note sheet and some of the air is sucked out of the chamber D by way of the port F², channel F' and port F, then the diaphragm E immediately moves downward to 35 its normal position, thus allowing the valve L to drop, thus closing the valve seat N and opening the valve seat O so that the pneumatic I receives atmospheric air by way of the seat O, chamber H and channel H', to 40 allow the pneumatic I to expand. When this takes place the rod J moves downward and consequently the piano action returns to its normal position of rest.

From the foregoing it will be seen that the 45 diaphragm E and the valve L are quickly actuated, and consequently a very quick response of the pneumatic I is had and without danger of leakage of air at any of the working parts. It will also be noticed that by 50 having the valve faces L', L² made of leather or the like, and in spherical shape, a noiseless opening and closing of the valve L takes place, especially as the air in rushing through the valve seats N and O at the point of closing or opening of the valve L does not strike 55 any sharp edges on the spherical valve faces L', L², and hence no hissing sounds are produced.

Having thus described our invention, we 60 claim as new and desire to secure by Letters Patent:

1. A pneumatic valve mechanism for self playing instruments, comprising a valve chest having a suction chamber, a dia- 65 phragm chamber having a port in its bottom,

a diaphragm between the said suction chamber and the said diaphragm chamber, a channel below the diaphragm chamber and into which opens the port thereof, the channel being in connection with a tracker board, a minute connection between the said suction chamber and the said channel, a valve chamber connected with the said suction chamber and the atmosphere, a valve in the said valve chamber and controlled by the 70 said diaphragm, and a pneumatic controlled by the said valve and connected with the said valve chamber.

2. A pneumatic valve mechanism for self playing instruments comprising a valve chamber, a suction chamber, a diaphragm chamber having a port in its bottom, a channel below the diaphragm chamber and with which the said port opens, said channel having one end extending up and opening 80 into the suction chamber and its other end in connection with a tracker board, a diaphragm between the suction and diaphragm chambers, said diaphragm extending over the channel and having a minute opening 85 therein, a valve in the valve chamber and having its stem engaging the diaphragm, and a pneumatic controlled by the valve.

3. A pneumatic valve mechanism for self playing musical instruments, comprising 95 a valve chest having a suction chamber, a diaphragm chamber having a port in its bottom, a channel into which opens the said port, said channel having a minute connection with the suction chamber a diaphragm 100 between the said suction chamber and the said diaphragm chamber, a pneumatic a valve chamber provided with valve seats and having connection with the pneumatic and by one valve seat with the atmosphere, 105 and by the other valve seat with the said suction chamber, and a self closing double valve having spherical faces and normally seated on the said seat connecting the said suction chamber with the said valve chamber, 110 the stem of the said double valve being seated on the said diaphragm for the latter to actuate the valve to close the valve seat to the atmosphere and to connect the suction chamber with the said valve chamber. 115

4. A pneumatic valve mechanism, comprising a valve chest made in top and bottom sections hinged together, the valve chest being provided with a locking plate secured to the free ends of the said sections 120 to lock the same together, a suction chamber formed in the bottom section and closed by the top section, a diaphragm chamber in the bottom chamber below the suction chamber and having connection with a tracker board by way of the said locking plate, a diaphragm between the said suction chamber and the said diaphragm chamber, a valve chamber in the said top section and having a channel extending through both 125 130

sections, a pneumatic having its fixed member secured to the underside of the said bottom section, the said channel opening into the said pneumatic by way of its fixed member, and a valve in the said valve chamber and controlling a port to the atmosphere and a port leading into the said suction chamber.

In testimony whereof we have signed our names to this specification in the presence 10 of two subscribing witnesses.
